PROCESS FOR MAKING BAGS AND THE LIKE

Adolph Potdevin, Garden City, N. Y., assignor to
 Potdevin Machine Company, Brooklyn, N. Y., a
 corporation of New York

Application September 30, 1932, Serial No. 635,495

3 Claims. (Cl. 93—35)

This invention is directed to a method of and apparatus for use in connection with the making of bags particularly bags of glassine and other fragile materials.

5 In the drawing accompanying this application:

Fig. 1 is a plan view of a machine or apparatus adapted for the practice of my invention;

Fig. 2 is a side elevational view of the same; and

10 Figs. 3 and 4 are views of bags embodying my invention.

Referring to the drawing in detail, the material from which the bags are to be made is taken from a supply roll 1, the web 2 passing about 15 rollers 3 and 4 to be brought into contact with circumferentially adjustable gluing disc segment 5.

After receiving the stripe of glue or other adhesive which is shown in Fig. 1 and designated 20 6, the material is forwarded to the notching devices 7, one at either side of the machine, these devices being rotated about axes parallel to the web travel and adapted to cut notches 8 in opposite edges of the web, while the web is in web 25 form as distinguished from a tube. The notches 8 are at bag lengths apart, and as the notching devices 7 move transversely of the web on their shafts 9 the web may be varied in speed to vary 30 the spacing of the notches without the necessity of changing the setting of the notchers. As above mentioned the gluing disc 5 is circumferentially adjustable, so that the terminals of the stripes 6 may be varied in accordance with any change 35 in location of the notches 8, the notches to be positioned between adjacent ends of the stripes.

After passing the notching mechanism 7 the material goes through tubing mechanism where the notched edges of the web are folded over toward each other into overlapped relation to bring the stripe of adhesive 6 over upon the main body of the web 2 and provide a longitudinal seam 10. In this tubing operation the outer ends 40 of the notches 8 are brought together to provide 45 one large opening 11 in the upper or seam wall of the tube (see Fig. 1), the notches terminating short of the tube edges.

The tube then passes to cutting-off mechanism 50 comprising rotary knife 12 and fixed knife 13 which severs the tube transversely into bag lengths. The knife 12 of the cutting off mechanism moves about an axis which is parallel to the travel of the tube and is so timed with respect to the speed of the tube that the tube is severed across the center of the opening 11 above referred to in the upper wall of the tube, so that each bag length, as shown in Fig. 1, will have a notch in one wall thereof at each end. These notches I have designated 14 and 15. A bag

length is shown at the left in Fig. 1 and has been designated 16.

The bag lengths are then satchel bottomed as shown in Fig. 3, the corners being tucked in as shown at 17 and 18, the upper wall folded back along the line 19, the portion 20 of this folded back portion which includes the notch 15 folded forward along the line 21, and the portion 22 of the lower wall folded forward upon the portion 20 of the upper wall.

10 In Fig. 4 I have shown a satchel bottom bag similar to the bag of Fig. 3, except that this bag has side tucks 23.

What I claim is:—

1. The process of forming bags from a web of material which process comprises notching opposite edges of the web, folding the web edges toward each other along lines intermediate the bottom of opposed notches to overlap the web edges and to bring the notches in overlapped relation into one wall of the tube thus formed, with the notches terminating short of the sides of the tube, and then severing the web transversely intermediate the sides of the notches to form bag lengths with a longitudinal notch in one 25 wall at each end of the bag length.

2. The process of forming bags from a web of material which process comprises forming notches in opposite edges of the web, said notches being positioned abreast of each other, folding 30 the web edges toward each other along lines intermediate the bottom of opposed notches to overlap the web edges and to overlap the notches and bring them into the seam wall of the tube thus formed, with the notches terminating short 35 of the edges of the tube, and then severing the web transversely midway of the sides of the notches to form bag lengths having a longitudinal notch in the seam wall at each end of the bag length.

3. The process of forming bags from a web of continuously advancing material which process comprises applying adhesive stripes in spaced relation aligned longitudinally of the web adjacent one edge thereof, notching opposite edges of the 45 web, the notches lying abreast of each other and those in the edge of the web to which adhesive has been applied lying in the spaces between adjacent ends of the adhesive stripes, folding the notched edges of the web toward each other into 50 overlapped relation to tube the web and to bring the notches into one wall of the web in overlapped relation, said notches terminating short of the tube edges, severing the tube transversely midway between the sides of said notches to provide 55 bag lengths with a longitudinal notch in the seam wall thereof at each end of the bag length, and finally bottoming one end of the bag length.

ADOLPH POTDEVIN.
